UNITED STATES PATENT OFFICE.

JOHN H. SMITH, OF PHILADELPHIA, PENNSYLVANIA, ASSIGNOR TO WESTINGHOUSE ELECTRIC & MANUFACTURING COMPANY, A CORPORATION OF PENNSYLVANIA.

CONDENSER.

Application filed October 12, 1926. Serial No. 141,221.

My invention relates to condensers for steam power plants and it has for an object to provide apparatus of this character wherein all of the tubes shall be so disposed as to be highly active in transferring heat, thereby making it possible to improve condenser design and performance.

With surface condensers, it is known that the outer tubes initially engaged by exhaust steam are more active from the standpoint of heat transfer than the more remote tubes. Therefore, it has occurred to me that the tubes located inside of the inner limit of good activity might be omitted and distributed outside, it being possible to do this with little increase in outside diameter of the tube nest and with little diminution in the activity of the prior outer zone of tubes. Apparently the reason for poor activity of the inner tubes of a condenser of this type is that such tubes tend to become surrounded with air and non-condensable vapors or gases, the latter serving to blanket or insulate the tubes and to resist penetration of steam. It is one of the principal objects of my invention to improve the performance of a condenser by reducing or avoiding blanketing or insulation of tubes by air or vapor. This may be effected by suitably spacing the tubes and arranging them so that each tube may do its proper share of work, while at the same time, providing for short and direct vapor paths in order to minimize the drop in pressure in the condenser.

My invention may be embodied in condensers of various types, as for example, in a condenser of the radial flow type. With condensers of the radial flow type, as heretofore constructed, the tubes of the central core are frequently not fully effective as heat transfer elements due to the general arrangement and to the operating conditions. In operation, condensation may be effected without deep penetration of steam into the tube nest and the tubes of the inner zone become surrounded with air and non-condensable gases which serve to blanket or insulate such tubes. Blanketing or insulation sets up resistance in the condenser. Under this condition, should the power plant load increase or should the temperature of the condenser cooling water increase, the blanketed or insulated tubes

would offer resistance to the required further penetration to effect condensation, resulting in less efficient performance. Blanketing or insulation of the inner tubes in this way, therefore, serves as added resistance during normal operation and to produce poorer performance whenever the load or the cooling temperature increases.

In accordance with my invention, for example, taking a standard design of radial flow condenser of a given size, I remove the inner core of tubes which have heretofore defined an insulated or blanketed core under many conditions and the tubes so removed are distributed about those remaining. In this way, the same number of tubes may be used with only slightly increased outside diameter of the tube nest, and such a distribution of tubes may be had as to provide for a reduction in distance of and resistance to vapor travel. Also the tube plates will not be increased in weight, for it is possible to core them substantially and thereby reduce them in weight over standard practice.

As is well understood in the art, a radial-flow condenser is one wherein the nest of tubes is substantially surrounded by a steam belt and the air and non-condensable gas off-take is located within the nest. While my invention, in its broader aspects, may be applied to condensers of other types, nevertheless, in its more specific aspects, my invention contemplates a condenser of the radial-flow type, or a type similar thereto. Accordingly, therefore, the drawings show a nest of tubes eccentrically located with respect to the shell to provide an arcuate steam space whose radial dimension diminishes away from the steam inlet and the off-take for air and non-condensable gases is located within the nest.

The application of my invention to a radial flow condenser perhaps will be better understood by reference to changes in a standard design. Taking a 40,000 sq. ft. condenser of the standard radial flow type having only a sufficient core for the air off-take, a central core of tubes of 64 in. in diameter may be removed and distributed about the outer tubes with an increase in outside diameter of only 7 in. Distribution of tubes in this manner provides for a relatively larger number of tubes coming into immedi-

ate and intimate contact with entering steam than is the case with the present standard arrangement, or, for that matter, than would be the case if more tubes are added to the present arrangement and the pitch thereof increased. A proportionately or larger total area between tubes is provided, and as above set forth, the distance of vapor travel and pressure drop through the condenser are obviously reduced whereas physical dimensions and distance of vapor travel as well as pressure drop are increased in the case of increased tube pitch arrangement.

A further object of my invention is, therefore, to reduce the distance of vapor travel in a condenser, to provide for better contact of entering steam with the tubes, and to avoid or to minimize the insulation or blanketing of tubes by air and non-condensable gases by providing a relatively shallow band of condensing tubes.

These and other objects are effected by my invention, as will be apparent from the following description and claims taken in connection with the accompanying drawings, forming a part of this application, in which:

Fig. 1 is a longitudinal sectional view of a condenser embodying my invention;

Fig. 2 is an end elevation of the condenser shown in Fig. 1;

Fig. 3 is an end elevation of a modified form of the condenser shown in Fig. 1;

Fig. 4 is a longitudinal cross sectional view showing a different form of air offtake;

Fig. 5 is a longitudinal sectional view showing an eccentric air core space in the tube nest;

Fig. 6 is an end elevation of the condenser arrangement shown in Fig. 5; and

Fig. 7 is a diagrammatic view added for the purpose of elucidating my invention.

Referring first to Fig. 7, in order that my invention may be more readily understood, I show a tube nest having a radial thickness

(a) only sufficient core space being left to provide for the usual air offtake. For example, such an offtake usually requires a space of approximately 15 in. in diameter.

My improved tube nest is in the form of an annular band of radial thickness (d), the omitted inner core annulus of radial thickness (b) having been added about the periphery of (a), thereby increasing slightly the radius of the tube nest by an amount (c).

As already pointed out, with a 40,000 sq. ft. condenser, it was found that a core amounting to 64 in. diameter could be removed and the tubes thereof distributed outside with an increase in outside nest diameter of only 6 in.

Having shown the possibility of the removal of core tubes and the distribution thereof about the periphery, possibly it may be well to emphasize again the reason for doing this. Theoretically, from the stand-

point of the resistance offered to and the distance of vapor travel, it would be better to provide a condenser having a single row of tubes; however, this is obviously impracticable on account of dimensional difficulties. Bearing in mind that possibly better performance might be secured by an approach to this ideal condition and bearing in mind that the central core of tubes of a standard condenser would frequently be jacketed or insulated by stagnant air and vapors, I have devised the present construction, which is advantageous for the following reasons:

1. The distance of vapor travel through the tube nest is diminished;

2. The permissible spacing and distribution of tubes is such that immediate and more intimate contact of steam therewith is assured and also the steam passes therethrough more readily and its residual velocity energy is more effective through the tube nest.

3. Due to the larger number of tubes coming into contact with the steam and to the decreased distance and resistance to travel of vapors through the tube nest, the cooling tubes act on the average much more efficiently.

Referring to Fig. 1, I show a condenser having a shell 10 provided with an inlet 11 for exhaust steam and with a hotwell 12 for condensate. Tube plates 13 are arranged at the ends of the shell and water box members 14 and 15 are preferably secured in place with respect to the shell ends, the tube plates 13 being clamped and held in place between the water box structures and the condenser ends as shown in Fig. 1. The tube plates 13 support a nest of tubes 16 in the usual way and intermediate tube supports 17 are preferably employed, these supports being mounted in any suitable way with respect to the interior of the shell.

The nest of tubes 16 preferably takes the form of a shallow annular band such that a very substantial core 18 without tubes is provided. Since the tube nest 16 is in the form of an annular band, it is possible to core the tube plates 13 substantially as indicated at 19, thereby saving both in weight and in material in so far as the tube plates are concerned.

Any suitable air offtake means may communicate with the core space. For example, in Fig. 1, I show an air offtake in the form of a tube or conduit 21 having lateral openings 22 communicating with the space 18, this conduit being connected to terminal portions 23 leading to any suitable air pump or ejector apparatus. In order that the tube or conduit 21 may constitute a brace or strut for the tube plates 13, I show the ends thereof terminating in flanges 24, which are secured in any suitable manner to the tube plates 13, the outlet members 23 preferably having flanged ends 25 which are secured to

the conduit 21. Drum constructions 26 and 27 are arranged inside of the water box members 14 and 15, respectively, these members being secured, at their inner ends, to 5 the tube plates and, at their outer ends, to the water box members and they are preferably so arranged as to provide for a fluid-tight fit with respect to the outlet members 23.

10 It is desired to arrange the condenser for two-pass operation, as shown in Figs. 1 and 2, diaphragms or plates 26' are enclosed in the water box 14, these diaphragms or plates fitting the exterior of the drum 26 and providing a space 28 communicating with the lowermost portion of the tube nest and having an inlet 29 for cooling water and a space 30 communicating with the uppermost portion of the tube nest and having 20 an outlet 31. The water box member 15 defines a space 32 for connecting the tube groups. Cooling water, therefore, enters the box space 28, passes through the lower group of tubes, then through the box space 32 to the upper group of tubes and then to the outlet box space 30 and the outlet 31.

In case it is desired to provide an arrangement, such as shown in Fig. 1, for single-pass operation, it is merely necessary, as 30 shown in Fig. 3, to omit the diaphragms or plates 26' in association with the drum 26 and to provide one of the water box structures with an inlet and the other water box structure with an outlet.

35 In some cases, it may be desirable to have the air offtake provided with outlets emerging from the bottom of the condenser. Such an arrangement is shown in Fig. 4, wherein the air offtake member 34 is supported by 40 hollow columns 35 emerging from the bottom of the condenser, these columns 35 being connected to any suitable air ejector or air removal apparatus. Also, in Fig. 4, I show a deflector 35 arranged above the air offtake member 34 for the purpose of minimizing the passage of condensate to the air offtake.

Owing to the fact that there is a tendency 50 for most of the work to be done in a condenser at the upper portion thereof, in Fig. 5, I show an arrangement wherein the nest is provided with an eccentric core space 37, the apparatus being otherwise similar to that already shown and described, that is, a condenser of this type may be either single or 55 double-pass; and, if made as a double-pass arrangement, obviously the diaphragms or division plates 38 would have to be so disposed in the water box 39 as to provide for 60 a substantially equal division of tubes.

In the drawings, I show a radial-flow 65 type of condenser, that is, the tube nest has disposed thereabout an arcuate steam space 40 whose radial dimension decreases away 70 from the steam inlet. The space 40 is de-

fined by the shell and the outermost boundary tubes of the nest, as clearly indicated on the drawings.

From the foregoing, it will be apparent 70 that I have devised a condenser wherein the air space is of decidedly larger minimum cross-sectional area than those heretofore in use. As already pointed out, it has heretofore been the practice merely to make this central air core space large enough to accommodate the air offtake. For example, this air offtake apparatus does not necessitate usually a space of more than 15 in. in diameter and, in so far as I am aware, it has never exceeded more than 18 in. in diameter. 75 In accordance with the present invention, it is not believed that any size of condenser would ever have an air core space less than 24 in. in diameter, or a space whose minimum cross-sectional area is 450 sq. in. In 80 most cases, this air core space will be much larger.

It is also characteristic of my improved 85 condenser that the ratio of inner periphery diameter of the tube nest to the outer periphery diameter thereof is much larger than that heretofore employed. In accordance with this invention, the air space has a much larger diameter, that is, the ratio of diameter of this space to the outside diameter of the 90 tube nest is not less than one-third, for example, it may be from one-third to one-half, depending upon the size of the structure and the amount of condensing surface. The ratio of one-half could be exceeded so far as 95 efficiency is concerned, but such apparatus would involve unwarranted cost. With a ratio of approximately one-third, or from one-third to one-half, a condenser may be made which is much more efficient than heretofore employed and which occupies but little more space than a condenser of standard design.

If my improved condenser is compared 100 with one of standard design, for the same size, it will be found that the tube nest is only slightly larger in diameter and the core space diameter is relatively much larger.

Therefore, my invention differs over prior 115 art in that the air core area and diameter are substantially larger than those heretofore employed, with the result that, for the same size of condenser, the maximum diameter of the tube nest is only increased by a small amount and the performance of the 120 condenser is greatly improved for the reason that the spacing and distribution of tubes provides for shorter vapor paths through the tube nest and less resistance to vapor flow, with the result that the steam comes into immediate and intimate contact with the tubes and that the resistance to and the path of vapor flow through the tube nest are greatly diminished, thereby making it 125 possible to utilize to the best advantage the 130

residual velocity possessed by steam in passing through the tube nest. By the use of my invention, I am able to improve decidedly the capacity of a condenser of a given size 5 for the reason that all of the tubes of the annular nest operate at a high rate of heat transfer. For example, assuming a standard 40,000 sq. ft. radial flow condenser to be redesigned in accordance with my invention, it 10 would have a much larger capacity.

While I have shown my invention in several forms, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims. 15

20 What I claim is:

1. A condenser comprising a shell encompassing a substantially hollow annular nest of tubes, and an offtake within the nest and defining with the inner boundary tubes a 25 substantially annular core space for collecting air and non-condensable gases from the nest and for supplying collected air and non-condensable gases to the offtake.

2. A condenser comprising a shell having 30 an inlet, a hollow nest of tubes within the shell and spaced therefrom so that a substantial portion of the outermost tubes of the nest define, with the shell, an arcuate steam delivery space in communication with 35 said inlet, and an air offtake conduit extending longitudinally within and surrounded by

the tube nest and spaced from the inner boundary tubes so as to provide an intervening core space or chamber for collecting air and non-condensable gases from the nest 40 and for supplying collected air and non-condensable gases to said offtake.

3. In a condenser, the combination of a shell having an inlet for exhaust steam and a condensate outlet, a substantially annular 45 nest of tubes defining an inner core space for air and non-condensable gases, the diameter of said space being not less than one third of the outside diameter of the nest, the outer boundary tubes of said nest being 50 freely and uninterruptedly exposed to the entering steam and the inner boundary tubes defining said core space, an air offtake communicating with said space, and means for circulating cooling water through the tubes. 55

4. In a condenser, the combination of a shell having an inlet for exhaust steam and a condensate outlet, a relatively shallow substantially annular band of tubes disposed within the shell and defining therewith an arcuate steam delivery space, an air offtake arranged substantially centrally with respect to said nest and spaced from the inner boundary tubes of said nest to define an intervening space for the reception of air and non-condensable gases from said nest, and means for circulating cooling medium through the tubes. 60

In testimony whereof, I have hereunto subscribed my name this 30th day of September, 1926. 65

JOHN H. SMITH.
